UNITED STATES PATENT OFFICE.

WILLIAM F. HENKE, OF NORWOOD, OHIO, ASSIGNOR TO THE CINCINNATI FROG & SWITCH COMPANY, OF CINCINNATI, OHIO, A CORPORATION OF OHIO.

EXTENSION-RAIL CLAMP.

1,427,737.

Specification of Letters Patent. Patented Aug. 29, 1922.

Application filed June 3, 1922. Serial No. 565,865.

To all whom it may concern:

Be it known that I, WILLIAM F. HENKE, citizen of the United States, residing at Norwood, in the county of Hamilton and State 5 of Ohio, have invented certain new and useful Improvements in Extension-Rail Clamps, of which the following is a specification.

The present invention relates to clamps intended for securing extension rails to the 10 ends of permanent rails, or, in other words, by means of these clamps, it is possible to adjust the length of a track from time to time in order to advance hoisting and conveying machinery for removing material located at the end of the track.

The invention is particularly useful in connection with coal and ore mining and excavation in general. The end of the permanent track is generally laid as close as possible to 20 a pile of coal, for instance, which is to be removed. As the edge of the pile recedes, the limit of reach of the hoisting machinery will soon be exceeded and a longer track required. By means of these clamps, a pair of rails may 25 then be quickly and firmly secured to the end of the permanent track. These extension rails may subsequently be further advanced as necessity requires, and easily reattached to the permanent track.

30 One embodiment of the invention is illustrated in the accompanying drawing, and:

Figure 1 is a top plan view of a track with the extension rails secured by means of the clamps forming the subject matter of the 35 present invention,

Figure 2 is a transverse sectional view along line 2—2 of Figure 1, and

Figure 3 is a side elevation of Figure 2.

The reference numeral 10 represents a pair 40 of rails forming a permanent track and to the ends of these rails a pair of tapering switch points 11 are secured in the usual manner, by means of fish plates 12 and bolts 13. These switch points are both tapered inwardly, as seen in Figure 1, so that the outer sides 14 of the switch points form an acute angle with the inner parallel lines 15 of the rails 10 and switch points 11. Along the tapered sides of the switch points are placed 45 a pair of extension rails 16 which are preferably held together by means of a tie rod 17 at their extreme free ends 18, so that the distance between the free ends of the rails is exactly the same as between the rails 10 of

the permanent track. For this reason, the 55 extension rails have to be bent, as at 19, in order to lie flat against the tapered sides of the switch points 11. As seen in Figure 2, the foot or bottom flange 20 of each switch point 11 is undercut, as at 21, in order to rest 60 on the bottom flanges 22 of the extension rails and insuring that the heads of the extension rails and the switch points become perfectly level.

The extension rails are firmly held to the 65 switch points by means of a pair of clamps. These clamps, as best seen in Figures 2 and 3, each consists of a flat base portion 23 upon which the switch point flange 20 and the flange 22 of the extension rail 16 rest. This 70 base portion terminates at one end with a jaw 24 reaching around the edge of the extension rail flange 22 and the opposite end of the base portion 23 of the clamp has a similar jaw 25 engaging the top of the flange 20 of 75 the switch point. This jaw is continued inwardly and upwardly to rest against the top of the flange 20 as well as against the web 26 of the switch point, terminating with a perpendicular portion 27. Extending transversely to the base portion 23 and the jaws 24 and 25, is a flat flange 28 reaching from 80 end to end of the clamp, as best seen in Figure 2, and in alignment with the base portion 23 are reinforcing wings 29 for the 85 flange 28, forming a cross therewith, as seen in Figure 3.

In order not to be affected by gravel or earth adhering to the edges of the flanges 20 and 22, the jaws 24 and 25 are looped, as at 90 30 and 31, so as to be spaced from the edges of the flanges. The inner face 32 of the upright portion 27 is inclined, as regards the axis of the clamp, which coincides with the axis of the rails 16 and this inclination conforms to the angular taper of the switch points. In this manner, when the clamp is slipped under the extension rail 16 and pushed over the flanges of said rail as well as of the switch point, the inner face 32 will 95 abut along the tapered side of the switch point while the clamp will be situated at right angles to the deflected rear end 33 of the extension rail. In this position, the clamp is driven as far back as it will go along 100 the extension rail until a firm grip is had between the same and the switch point.

At 34 is represented the edge of a pile of

coal or gravel for instance, which is to be removed by means of hoisting and conveying machinery carried along the permanent track. The relative distance from the ends 5 of the permanent track and the pile of material 34 is supposedly greater than the reach of the hoisting machinery placed at the end of the permanent track 10. In order now to advance the hoisting machinery, 10 a pair of the extension rails 16 are laid along the switch points 11 and clamped thereto so that the free ends 18 of the extension rails nearly touch the edge of the pile 34. The hoisting and conveying machinery may now 15 be run out onto the extension rails and when the material has been removed up to the line 35, the reach of the hoisting machinery is again exceeded and the said machinery is then run back on the permanent track while 20 the clamps are loosened and the extension rails 16 advanced, as shown in dot and dash lines at 36, to near the edge of the pile of material. The extension rails are again bent at the proper point and then again secured 25 by means of the clamps, as already described. This procedure is repeated until, finally, the rear ends 33 of the extension rails have reached the switch points 11 when no further extension is possible. This 30 done, the switch points 11 are detached from the ends of the rails 10 and attached to the free ends 18 of the extension rails while the rear ends of the extension rails 33 are secured, by means of fish plates and bolts, in 35 the usual manner, to the permanent track 10. Another pair of extension rails are then secured in a similar manner, to the switch points 11, which are now located at the free ends of the old extension rails 16. 40 It will be noted that the bend at 19 on the extension rails, is not greater than the flexibility of the rails will permit and that this bend moves gradually nearer the free ends 33 of the extension rails as the latter 45 are advanced along the switch points.

It should also be noted that with this arrangement, a much quicker and more accurate shifting of the rails is possible than in the usual way, when certain length sections 50 of rails are used and secured by fish plates to the ends of the permanent track. The adjustment of a few inches in length is now possible instead of an advance of several feet each time.

Having thus described the invention, 55 what is claimed as new is:

1. In combination with a permanent track terminating with a pair of wedge ends, a pair of rails mating with the sides of said wedge ends, and a clamping member for each rail having opposing jaws adapted to engage with the flanges of said ends and rails respectively.

2. In combination with a permanent track terminating with a pair of wedge ends rigidly secured to the permanent track, a pair of rails mating with the sides of said wedge ends, and a clamping member for each rail having opposing jaws adapted to engage with the flanges of said ends and rails respectively.

3. In combination with a permanent track terminating with a pair of wedge ends rigidly secured to the permanent track, a pair of rails mating with the sides of said wedge ends, and a clamping member for each rail having opposing jaws adapted to engage with the flanges of said ends and rails respectively, said clamping member having a body portion fitting beneath the flanges of the rails and wedge ends.

4. In combination with a permanent track terminating with a pair of wedge ends rigidly secured to the permanent track, a pair of rails mating with the sides of said wedge ends, and a clamping member for each rail having opposing jaws adapted to engage with the flanges of said ends and rails respectively, said clamping member having a body portion fitting beneath the flanges of the rails and wedge ends and one of said jaws having an inclined inner surface of the same angularity as the wedge ends.

5. A clamp for rails comprising integral therewith a base portion and a loop shaped jaw at each end thereof; said base portion providing a seat for rail flanges and said jaws adapted to engage the top face of said flanges; one of said jaws having an abutment wall running perpendicularly to said base portion and at an inclination to the axis of the clamp and adapted to engage with the web of a rail, said base and jaws having perpendicular and transverse reinforcing flanges.

In testimony whereof I affix my signature.

WILLIAM F. HENKE. [L. S.]
